UNITED STATES PATENT OFFICE.

WILLIAM W. JACKSON, OF PHILADELPHIA, PA., ASSIGNOR TO ARTHUR M. BARNHART AND ALSON E. BARNHART, BOTH OF CHICAGO, ILL.

DESIGN FOR TYPE.

SPECIFICATION forming part of Design No. 17,130, dated February 22, 1867.

Application filed January 2, 1866. Serial No. 17,488. Term of patent 11 years.

To all whom it may concern:

Be it known that I, WILLIAM W. JACKSON, a citizen of the United States, residing in Philadelphia, county of Philadelphia, and State of Pennsylvania, have invented and produced a new and original Design for a Font of Printing-Types, of which the accompanying specimen or impression is an exact representation, and is made a part of this specification.

10 The character of the design is a heavy broad-face ornamented, ray-shade; and it consists of capitals, figures, dollar-mark, character &, and points.

15 The special features are the vertical, horizontal, diagonal, and curved lines, which are concave at one or both ends, terminating in sharp points. The center strokes in B P R are heavy, curve downward, and do not connect with the vertical lines on the ray-shading, which is a series of fine lines curved, parallel, 20 or waved on the right side and lower edge of the heavy-faced line and at a short distance therefrom, and following the configuration thereof, and thereby appearing as a reflection, so to speak, of the heavy lines. 25

I claim—

The design for a font of printing types, the character of which is a heavy broad-face, ornamented, ray-shade type, the horizontal, diagonal, vertical, and curved lines being concave at one or both ends, and a combination 30 of the heavy with the fine shade lines, as described, and shown in the accompanying typographical illustration.
